US00D943679S

(12) **United States Design Patent** (10) Patent No.: **US D943,679 S**
(45) Date of Patent: **** Feb. 15, 2022**

(54) **LLAMA FIDGET TOY**

(71) Applicant: **Yuezeng Huang**, Jiujiang (CN)

(72) Inventor: **Yuezeng Huang**, Jiujiang (CN)

(**) Term: **15 Years**

(21) Appl. No.: **29/777,751**

(22) Filed: **Apr. 8, 2021**

(51) LOC (13) Cl. **21-01**

(52) U.S. Cl.

USPC **D21/468**; D21/338; D21/350; D21/576;
D21/652

(57) **CLAIM**

The ornamental design for a llama fidget toy, as shown and described.

DESCRIPTION

FIG. 1 is a perspective view of a llama fidget toy showing my new design;

FIG. 2 is a front view thereof;

FIG. 3 is a rear view thereof;

FIG. 4 is a left side view thereof;

FIG. 5 is a right side view thereof;

FIG. 6 is a top plan view thereof; and,

FIG. 7 is a bottom plan view thereof.

1 Claim, 7 Drawing Sheets
